CLAIM

The ornamental design for a liquid dispensing container, as shown and described.

DESCRIPTION

FIG. 1 is a front, top perspective view of a liquid dispensing container showing my new design;

FIG. 2 is a front elevational view thereof;

FIG. 3 is a right side elevational view thereof, the left side elevational view being a mirror image thereof;

FIG. 4 is a rear elevational view thereof;

FIG. 5 is a top plan view thereof;

FIG. 6 is a bottom plan view thereof; and,

FIG. 7 is a bottom, side perspective view thereof.

The broken lines appearing in FIGS. 6 and 7 showing concentric ovals surrounding a protruding ring on the bottom of the liquid dispensing container form no part of the claimed design.
